2 - p - METHOXYBENZENESULFONAMIDE - 5 - ISO-BUTYL - 1,3,4 - THIADIAZOLE IN THE ORAL TREATMENT OF ACNE

Joseph Raymond MacDougal, Montreal, Quebec, Canada, assignor to Frank W. Horner Limited, Montreal, Quebec, Canada

No Drawing. Filed Nov. 6, 1959, Ser. No. 851,271

3 Claims. (Cl. 167—55)

This invention relates to an improved method in the treatment of acne particularly pustular acne, and more particularly to the treatment of acne by means of an orally ingested thiadiazole, more particularly 2-p-methoxybenzenesulfonamide-5-isobutyl-1,3,4-thiadiazole.

In severe cases of acute pustular acne, local therapy alone is of little value. The specific systemic measures usually employed in addition to local therapy depend upon the seriousness of the skin condition. Additional measures which have been used in the past include: hormone therapy, particularly diethylstilboestrol; dietary control; vitamin supplements, particularly vitamin A and vitamin C; ultraviolet and X-ray therapy; administration of toxoids and vaccines; and use of antibiotics, such as sulfonamides; penicillin, erythromycin, chloramphenicol, oleandomycin, tetracycline and novobiocin. Isoniazid has also been used. Most consistent results have been achieved with chloramphenicol and erythromycin. Nevertheless, treatment with antibiotics is unsatisfactory since, while a favourable response to usually obtained, this is followed by a new flare-up, and relapses are frequent after discontinuance of the antibiotics. The other forms of drug therapy are also not completely effective.

In pending application Serial Number 824,176 filed in the name of J. L. Cohen on July 1, 1959, now U.S. Patent No. 3,072,527, there is disclosed an improved method for the treatment of acne by the administration of tolbutamide. The utility of tolbutamide in the treatment of acne is unexpected, since tolbutamide has no bactericidal effect.

However, it is known that a 1.0 g. dosage of tolbutamide lowers blood sugar levels about 10% in normal individuals. While this lowering of the blood sugar is not serious, there may be cases where acne is to be treated when such lowering of blood sugar levels may be critical.

It is an object of the present invention to provide an improved oral therapy for the relief of symptoms of acne.

This object is achieved in the method of treating acne which comprises: selecting a human having acne; and feeding said human a therapeutically effective dose of 2-p-methoxybenzenesulfonamide-5-isobutyl-1,3,4-thiadiazole.

Usually, the therapy consists in the ingestion, by the patient suffering from acne, of tablets containing the thiadiazole. Although doses of 2-3 grams per day of the thiadiazole may be safely used, effective doses will be in the range of 0.5-1.0 gram per day.

A convenient form of treatment is the use of tablets containing from about 250 mg. to about 1000 mg. of the 2 - p - methoxybenzene - sulfonamide-5-isobutyl-1,3,4-thiadiazole, with an especially convenient amount being 500 mg. of the thiadiazole per tablet. Preparation of such tablets is given below.

EXAMPLE I.—TABLETS

The following proportions of ingredients were used:

	Gm.
2 - p - methoxybenzenesulfonamide-5-isobutyl-1,3,4-thiadiazole	50.0
D and C Orange #4	0.025
Orange colored starch	6.5
Sodium bicarbonate	3.1
Magnesium stearate	0.8

2

The orange colors were dissolved in a granulating solution consisting of a 24% solution of gelatin and acacra in water. The thiadiazole was then granulated with 1.0 gm. of the colored starch, the amount of granulating solution originally used being sufficient to result in a dry granulation procedure. The balance of the starch, the sodium bicarbonate and the magnesium stearate were then intimately mixed therewith and the mixture was compressed into tablets.

The proportions used were sufficient to result in the preparation of 100 tablets, each weighing 620 mg. and containing 500 mg. of the thiadiazole.

EXAMPLE II.—CAPSULES

In this case 50.0 gm. of 2-p-methoxybenzenesulfonamide-5-isobutyl-1,3,4-thiadiazole was intimately mixed with 1.0 gm. of a light mineral oil. 100 capsules each containing 500 mg. of the thiadiazole were then prepared by placing 510 mg. of that mixture into hard gelatin capsules.

A series of patients were treated with 2-p-methoxybenzenesulfonamide-5-isobutyl-1,3,4-thiadiazole according to the method of the present invention. The results are tabulated in Table I below.

Table I

No.	Diagnosis	Prior Treatment	Treatment with 2-p-methoxybenzenesulfonamide-5-isobutyl-1,3,4-thiadiazole	
			Side Effects	Evaluation
1.....	Cystic acne, recurring furunculosis.	Antivaccine progesterone, antibiotics X-ray, cryotherapy.	None after 64 days.	Good; patient free of acne type of infection, feels better.
2.....	Furunculosis, relapsing.	Antibiotics.....	None after 89 days.	Good; furuncles have not relapsed.
3.....	Furunculosis.	Antibiotics antivaccine serum globulin.	54 days treatments.	Good; pustules dried up quickly.
4.....	Severe cystic acne.	Progesterone serobacterium CO_2 slush.	None after 101 days.	Good; appears to prevent outbreak of new cysts premenstrually.
5.....	Furunculosis.	Antibiotics, vaccine.	None after 90 days.	Good.
6.....	Cystic acne.....	None.....	None after 42 days.	Slow steady improvement.

It is seen from the above table that 2-p-methoxybenzenesulfonamide-5-isobutyl-1,3,4-thiadiazole is effective in the treatment of acne.

The effect of 2-p-methoxybenzenesulfonamide-5-isobutyl-1,3,4-thiadiazole on the blood sugar of normal non-diabetics compared to the effect of tolbutamide on normal patients is shown below in Table II. It will be observed that the data is expressed as percentage of initial blood sugar following ingestion of 3000 mg. of 2-p-methoxybenzenesulfonamide-5-isobutyl-1,3,4-thiadiazole and the average percentage of initial blood sugar of 50 normal patients following the ingestion of a dose of 50 mg./kg. body weight of tolbutamide taken from the reference Mirsky et al: Metabolism, 5, 875 (1956).

3
Table II

Hours after ingestion	3000 mg. 2-p-methoxybenzene- sulfonamide-5-isobutyl- 1,3,4-thiadiazole Number—			50 mg./kg. body weight tolbutam- ide
	7	8	9	
0.....	100	100	100	100
1.....	100	97	95	56
2.....				68
3.....				72
4.....	93	100	70	72
5.....	93	100	79	56
6.....				

It will be seen from Table II that while tolbutamide causes a rapid and substantial drop in blood sugar levels at dosage levels of 50 mg./kg. body weight, 2-p-methoxybenzenesulfonamide-5-isobutyl-1,3,4-thiadiazole, in the majority of cases, causes no significant decrease in blood sugar at approximately the same dosage (3 grams total). It is also to be emphasized that the dose of tolbutamide with which the results of the present invention are compared is 50 mg./kg.

4

I claim:

1. The method of treating acne which comprises orally administering to a human affected with acne a daily dose of 0.5-3.0 grams, in individual doses of 250-1000 mg. of 2-p-methoxybenzenesulfonamide-5-isobutyl-1,3,4-thiadiazole.
2. The method of claim 1 wherein the thiadiazole is fed in a dosage unit form containing about 0.5 gm. of said thiadiazole.
3. The method of claim 2 wherein the thiadiazole is fed in tablet form.
